UNITED STATES PATENT OFFICE.

ERNEST G. GOODWIN, OF PELHAM, NEW YORK, ASSIGNOR TO STANDARD COUPLER CO.,
OF NEW YORK, N. Y., A CORPORATION OF NEW JERSEY.

FRICITION DRAFT RIGGING.

Application filed December 11, 1923. Serial No. 679,883.

To all whom it may concern:

Be it known that I, ERNEST G. GOODWIN, a citizen of the United States, residing at Pelham, in the county of Westchester and 5 State of New York, have invented certain new and useful Improvements in Friction Draft Rigging, of which the following is a full, clear, and exact description, such as will enable others skilled in the art to which 10 it appertains to make and use the same.

This invention relates to improvements in apparatus for yieldingly resisting stresses and more especially in some of its details to improvements in friction, buffing and draft 15 gear for use in connection with railway cars and the like.

The general object of the invention is the provision of an improved friction draft gear, which is light, strong, wear-resistant, 20 and susceptible of ready repair and replacement of parts, and the parts whereof are readily interchangeable with those of old draft gears of similar type.

Another object is to provide in a draft 25 gear of the type mentioned a combined spring plate and friction center wedge block of improved integral cast construction, which is light and well adapted to endure under severe service conditions, being 30 moreover economical in production and maintenance costs.

Other objects will be in part pointed out in connection with the following detailed 35 description of a preferred embodiment of the invention, and will be in part obvious in connection therewith.

The invention accordingly comprises the features of construction, combinations of elements, and arrangement of parts which 40 will be exemplified in the apparatus herein-after described and the scope of the application of which will be indicated in the claims.

For a more complete understanding of the nature and objects of the invention, reference is had to the accompanying drawings, showing an illustrative but preferred embodiment, and in which:

Fig. 1 is a fragmentary perspective view 50 of a friction draft gear embodying the invention, parts being broken away for clearness of disclosure;

Fig. 2 is a fragmentary plan view, parts being shown in central horizontal section;

Fig. 3 is a front end elevation of the 55 center friction block; and

Figs. 4 and 5 are respectively side and end views of the center friction block, parts being shown in central section.

Certain features of the present invention are disclosed in applicant's prior application, Serial No. 555,375, filed April 18, 1922, and to the extent of the common disclosure the present application may be considered a continuation of the prior application.

Referring now to the drawing for a detailed description of the embodiment of the invention there disclosed, the draft gear is shown as mounted between sills 10 (indicated in dot-and-dash lines in Fig. 2) which may be the draft sills of a railway car or 70 the like, being secured in a known manner in the underframing construction of the car. Stops 11 and 12 are preferably riveted to the inner faces of the draft sills 10, forming abutment stops for the forward and rear 75 follower plates 13 and 14 extending between the draft sills. As will be understood, draft and buffing stresses are transmitted to the follower plates and through them to the buffing elements themselves, 80 through a draw bar which may be of standard preferred construction. Such stresses will therefore be cushioned through the draft rigging and transmitted to the car 85 frame.

The draft and buffing elements proper are mounted between the draft sills, lying between the follower plates, and include a spring barrel 15 abutting against a flange 16 extending from a friction box 17, and providing a seat for transmitting stresses between the spring barrel and friction box. The friction box is preferably of forged or cast metal, and side friction blocks 18 and a center friction block 19 are partially housed 95 within the mouth of the friction box. Inner and outer concentric springs 20 and 21 are housed within the spring barrel abutting at adjacent ends with one of the follower plates as 13 and at their opposite ends 100 abutting with spring seats provided on the center friction block.

The spring barrel 16 is made up of one or more, preferably two, wrought metal plates bent into approximately rectangular, or 105 similar, polygonal form and having overlapping riveted edges 22 which are preferably arranged at the corners or angles of the spring barrel so as to occupy the space available therefor without in any way limiting 110

- the size of draft springs used or interfering with the application of the draft yoke, which is made in a standard size. The spring barrel seats at one end against the corresponding follower plate 13 and at the opposite end against the seat formed by the flange 16 as mentioned, the friction box being provided with integral lugs 23 and 24 for engagement with the end edges of the barrel.
- 10 There are but two of these lugs, one being located on each lateral side of the friction box, each being relatively long peripherally and engaged with the curved surface of the barrel intermediate the angles thereof, so as to afford ample support to hold the barrel and friction box in proper cooperative positions. The friction box is preferably rectangular, being provided with inner laterally disposed friction surfaces for cooperation with the opposed friction surfaces of the side friction blocks, as clearly shown in Fig. 2.

The side friction blocks may be of a standard type of construction, preferably of cast metal, but the center block 19 is of special improved construction in which the block proper and the spring plate, adapted for forming seats for the draft springs, are cast integrally as a single specially reinforced unit. As shown, the center block is preferably of hollow cast construction, having inclined friction faces for cooperating with the opposed contacting faces of the side friction blocks. All the friction blocks are 35 preferably wedge or triangular shape as shown. The center friction block is substantially rectangular in base plan with rounded corners to conform approximately to the inner transverse contour of the spring 40 barrel, and is provided with an external peripheral base flange 25 formed integral with the block and forming not only a stiffening and rigidifying member at the base of the friction block where service stresses are particularly heavy, but it also forms an extension from the base of the block to provide a seat extension for the corresponding end of the outer draft spring 21. Also adjacent the base of the center friction block and substantially forming the base wall thereof is an internal or inwardly extending flange 26 disposed around the base of the block. This flange 26 also performs the double function of rigidifying the base of the block and providing a seat for the inner draft spring 20 for which purpose it may be recessed as indicated at 27.

From the foregoing, it will be seen that the exterior and interior base flanges 25 and 60 26 cooperates to rigidify the center friction block at the base where service stresses are heaviest, thus permitting a light hollow structure without sacrificing requisite rigidity to effectually withstand the stresses to 65 which the different regions of the block are

subjected. These two flanges also provide in effect an integral spring plate for cooperating with the draft springs, thus entirely avoiding any separate spring plate construction, which is found in practice to be expensive and likely to get out of order.

The exterior flange 25 at the top and bottom of the block 19 (see Fig. 1) is positioned to horizontally overlap the inner overhanging edges 28 of the friction box, so as to hold the block and friction blocks in assembled relation. In assembling the parts, the center block is placed in position from the inner side of the friction box and these two parts are supported in position by contacting of the flanges 25 with the overhanging walls 28, the side friction blocks being then placed in position from without. These assembled parts are then readily placed as a unit in position between the follower plates 13 and 14. The center block constructed and described is readily interchangeable with center blocks employed in similar types of friction draft gear, but employing a separately constructed attached spring plate.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebeneath.

Having described my invention, what I claim as new and desire to secure by Letters Patent, is:

1. In a friction draft gear, the combination with a spring barrel, draft springs disposed within said barrel and a friction box arranged adjacent said barrel, of center and side friction blocks disposed within said box and having friction faces cooperating with corresponding friction faces of the friction box and with each other, said center friction block being hollow and having a spring plate formed integral therewith to provide seats for the draft spring, the spring plate being formed by an external peripheral base flange 110 formed on the center block and providing a seat extension for an end of one draft spring, the spring plate being further formed by an interior flange extending around the base of the center block and being provided with a depressed seat for the reception of a second draft spring, the exterior and interior flanges cooperating to provide complementary rigidifying members adjacent the base of the center block, the friction box being provided 115 120 125 130

with inner walls to cooperate with said external flange for retaining the block in assembled position in the friction box.

2. In a friction draft gear, the combination with a spring barrel, draft springs disposed within said barrel, and a friction box arranged adjacent said barrel, of center and side friction blocks disposed within said box and having friction faces cooperating with corresponding friction faces of the box and with each other, said center friction block being hollow and having a spring plate formed integral therewith to provide seats for the draft springs, the spring plate being formed by an external peripheral base flange formed on the center block and providing a seat extension for an end of one draft spring, the spring plate being further formed by an interior flange extending around the base of the center block and being provided with a depressed seat for the reception of an end of a second draft spring, the exterior and interior flanges cooperating to provide complementary rigidifying members adjacent the base of the center block.
3. In a friction draft gear, the combination with a spring barrel, draft springs disposed within said barrel, and a friction box adjacent which said barrel is disposed, of center and side friction blocks disposed within said box and having friction faces cooperating with corresponding friction faces of the box and with each other, said center block having a spring plate formed integral with the base thereof to provide seats for the draft springs, the spring plate being formed

by complementary exterior and interior base flanges, the exterior base flange extending peripherally of the center block and providing a seat extension for one draft spring, the inner flange extending around the base of the block and being provided with a depressed seat for receiving an end of a second draft spring, said exterior and interior flanges cooperating to rigidify the center block at the base portion thereof. 40

4. In a friction draft gear, the combination with a spring barrel, draft springs housed within said barrel, and a friction box arranged adjacent said barrel, of friction blocks disposed within said box and having friction faces cooperating with corresponding faces of the box and with each other, one of said blocks having a spring plate formed integrally at the base thereof to provide seats for the draft springs, an exterior peripheral flange extending integrally from the base of said block and providing a seat extension for the spring plate against which one of said springs rests, and providing furthermore, a rigidifying rib for the base of said block, said spring plate being also formed with a depressed seat lying inwardly of said external flange and adapted to receive the adjacent end of a second draft spring. 50

In testimony whereof I affix my signature, in the presence of two witnesses.

ERNEST G. GOODWIN.
